SPAGHETTI FORK

Robert A. Balow, Eau Claire, Wis., assignor of a fractional part interest to Francis D. Hurd, Glen Ellyn, Ill.

Filed Sept. 15, 1971, Ser. No. 180,957

Term of patent 14 years

Int. Cl. D7—03

U.S. Cl. D54—12

FIG. 1 is a front elevational view of a spaghetti fork showing my new design;

FIG. 2 is a side elevational view thereof;

FIG. 3 is a rear elevational view thereof;

FIG. 4 is a top plan view thereof; and

FIG. 5 is a bottom plan view thereof.

I claim:

The ornamental design for a spaghetti fork, as shown.
